Attorney

UNITED STATES PATENT OFFICE.

LOUIS FRIEDMANN, OF VIENNA, AUSTRIA.

HEATING OF OIL DELIVERED BY LUBRICATING PUMPS.

Application filed November 6, 1920. Serial No. 422,362.

(GRANTED UNDER THE PROVISIONS OF THE ACT OF MARCH 3, 1921, 41 STAT. L., 1313.)

To all whom it may concern:

Be it known that I, LOUIS FRIEDMANN, citizen of the Republic of Austria, residing at Vienna, in the Republic of Austria, have 5 invented certain new and useful Improvements Relating to the Heating of Oil Delivered by Lubricating Pumps (for which I have filed applications for patents in Austria on April 10, 1920; in Poland on December 3, 1919; in Hungary on March 3, 1915; in Switzerland on March 1, 1915; in Germany on February 26, 1915; in Czechoslovakia on August 27, 1917, and in England on August 23, 1920), of which the following is a specification.

This invention relates to mechanically driven lubricating pumps, especially adapted for the lubrication of the inner parts of locomotive-mechanisms. By such pumps 20 the oil is fed to the different places, where it is to be consumed, so that the quantities of oil delivered by the lubricating pump are not returned in the oil container and therefore a circulation of oil can not occur.

25 The invention consists essentially in that the quantities of oil are heated by steam before they are entering into the lubricating pump.

For this purpose the oil container consists 30 in two chambers of which one is considerably smaller and is arranged in the lower part of the oil container, being connected with the suction lead of the lubricating pump, while the other chamber is formed by 35 the other much larger part of the oil container.

The smaller chamber is heated by steam and the return of the oil from this chamber to the container is prevented.

40 Thereby two rooms filled with oil of different temperatures are formed. The smaller chamber contains oil of approximately constant temperature, whereas the oil contained in the other larger chamber 45 i. e., in the oil container itself, will have a much lower temperature and will be heated very slowly and directly by the smaller chamber.

In known arrangements of this kind, in 50 which the oil is heated in such pumps, the whole quantity of oil contained in the oil container is heated and therefore when the

plant is first started, the oil is too cold, whereas after a certain period it becomes 55 too hot and this influences the working of the lubricating pump in a very deteriorating manner.

In the drawings:

Fig. 1 is a vertical view of an apparatus embodying my invention. 60

Fig. 2 is a longitudinal sectional view taken at a right-angle to Fig. 1.

Fig. 3 is a fragmental vertical sectional view of a modification.

Referring to the drawings, *a* is the oil 65 container in which pumps *b* are arranged in a known manner. *c* indicates the suction duct and *d* an oil chamber connected by passages *e*, *e'* with the oil container; *f* is a second chamber adjacent to the chamber *d* and is connected with a steam lead *g*. The cross-section of the passages *e*, *e'* is so small that after starting the pump *b* the oil current set up from the container *a* through thin passages to the chamber *d* attains such a velocity that the tendency of the 70 hot oil to return from the chamber *d* to the container is counteracted. If a very large area would be given to the passages *e*, *e'* the result would be that simultaneously a 75 flow of cool oil into the chamber *d* and a return of hot oil into the container would occur owing to the difference of temperature. By appropriately closing the passages *e*, *e'* it is of no consequence where these passages 80 are located whether at a higher or at a lower level. Preferably these passages are located below the top wall of the chamber *d*.

In the modification shown in Fig. 3 of the drawings the steam chamber *f*, instead 85 of being located below or adjacent the oil chamber, is located within the chamber *d*.

If the passages *e* and *e'* were of large area or if they communicated with the upper portion of the chamber *d* the oil heated 90 in the chamber *d* would be disposed to rise through the cooler oil and to escape at a rapid rate through said passages back into the oil container *a*.

The pumps *b* take up the heated oil from 100 the upper portion of the chamber *d* through the passages *e* and will thus counteract any tendency of the heated oil to flow back through the passages *e* and *e'* to the oil con-

tainer *a*. To this end the passages *e* and *e'* are preferably made of such area that the return of the oil from the chamber *d* to the container *a* is prevented at the effective speed of the pumps *d*.

In the operation of the apparatus cool oil will pass from the container *a* through the passages *e* and *e'* into the chamber *d* and, in flowing through said chamber to 10 the inlet passages *c* of the pumps, will be heated to the required degree.

It is to be understood that such changes and modifications may be made in the apparatus as may properly fall within the 15 scope of the appended claims.

Having described the preferred embodiment of my invention, what I claim is:—

1. An oil heating device for lubricating pumps, comprising a main oil supply chamber, an auxiliary oil chamber located in the bottom of said main oil chamber, said auxiliary oil chamber having restricted passages forming communication between the main and auxiliary oil chambers, for drawing oil 20 from said auxiliary chamber and forcing it to the parts to be lubricated, and means for heating oil contained in said auxiliary reservoir.

2. An oil heating device for lubricating pumps, comprising a main oil supply chamber, an oil heating chamber in communication with said main oil supply chamber, means for heating the oil within the oil heating chamber, the communication between 30 said chambers consisting of constricted apertures formed in the walls of said oil heating chamber adjacent the bottom of both of said chambers, and a pump for drawing heated oil from said heating chamber thereby causing oil to flow into the latter from the main chamber through said 35 constricted apertures.

3. An oil heating device for lubricating pumps, comprising an oil supply chamber, a lubricating pump for forcing oil to the parts to be lubricated, and means embodying a heating chamber to receive oil from said oil supply chamber and deliver it in heated 45 condition to said pump, the walls of said heating chamber having restricted passage-ways adjacent the bottom thereof for the flow of oil from the supply chamber to 50

replace heated oil withdrawn from the latter chamber by the pump.

4. An oil heating device for lubricating 55 pumps, comprising an oil supply chamber, a chamber for receiving oil from said supply chamber and having means for heating it, a pump connected to draw oil from said receiving chamber, said receiving chamber 60 being provided with constricted apertures forming communication between the bottom of said receiving chamber and the bottom of the supply chamber.

5. An oil heating device for lubricating 65 pumps, comprising an oil supply chamber, an oil heating chamber associated with said supply chamber, lubricating pumps connected to draw oil from the heating chamber, and means for heating the oil within 70 said oil heating chamber, the walls of said heating chamber having constricted passageways connecting the bottom of said supply chamber with the bottom of said heating chamber, the arrangement being such as to 75 permit the flow of oil from the supply chamber to the heating chamber in consequence of the withdrawal of oil from the heating chamber by the pumps and to prevent the backflow of heated oil from the heating 80 chamber to the supply chamber.

6. The combination of an oil supply chamber adapted to contain a relatively large body of cool oil, an auxiliary chamber in the lower portion of the supply chamber adapted to contain a relatively smaller body of oil and having restricted passages 85 for the flow of oil thereto from the supply chamber, means for heating oil contained in the auxiliary chamber, and a lubricating 90 pump connected to draw heated oil from the auxiliary chamber and operative to force such oil to the parts to be lubricated, said restricted passages permitting cool oil from the supply chamber to flow into the auxiliary chamber in consequence of withdrawal 95 of oil by the pump from the auxiliary chamber but preventing back flow of heated oil from the auxiliary chamber to the supply chamber.

In testimony whereof I have hereunto set my hand.

LOUIS FRIEDMANN.
